UNITED STATES PATENT OFFICE.

EDWIN FISHER, OF NEW YORK, N. Y., ASSIGNOR TO THE LOWELL MANUFACTURING COMPANY, OF BOSTON, MASSACHUSETTS.

DESIGN FOR CARPET.

SPECIFICATION forming part of Design No. 24,122, dated March 19, 1895.

Application filed February 23, 1895. Serial No. 539,487. Term of patent 3½ years.

To all whom it may concern:

Be it known that I, EDWIN FISHER, a citizen of the United States, residing at New York, county and State of New York, have invented and produced a new and original Design for a Carpet, of which the following is a specification, reference being had to the accompanying drawing, making a part of the same, and is sufficient to enable others skilled in the art to make and use my invention.

What I claim as new, and desire to secure by Letters Patent, is—

The design for a carpet, as shown in the accompanying drawing.

EDWIN FISHER.
